UNITED STATES PATENT OFFICE.

RUFUS BENZIGER AND FRANK GASS, OF JACKSONVILLE, FLORIDA.

WINDOW-FASTENER OR DOOR-CHECK.

1,366,689.

Specification of Letters Patent. Patented Jan. 25, 1921.

Application filed August 30, 1920. Serial No. 406,936.

To all whom it may concern:

Be it known that we, RUFUS BENZIGER and FRANK GASS, citizens of the United States, residing at Jacksonville, in the county of Duval and State of Florida, have invented certain new and useful Improvements in Window-Fasteners or Door-Checks, of which the following is a specification.

10 This invention relates to fasteners for swinging window sashes and the like.

The object of the invention is to provide a simply constructed and efficient device for fastening a swinging window sash, door or 15 the like in adjusted position.

Another object is to so construct such a device that it may be quickly and easily operated and yet will securely hold the sash against accidental release, and which is 20 strong and durable having few parts all of which may be readily replaced should they become worn or broken.

With these and other objects in view, the invention consists in certain novel features 25 of construction, as hereinafter shown and described and then specifically pointed out in the claims and in the drawings illustrative of the preferred embodiment of the invention.

30 In the accompanying drawings:

Figure 1 represents a perspective view of this improved fastener shown applied and in position for holding a window in open position.

35 Fig. 2 is a horizontal section through the window with the fastener shown in plan view and in closed position.

Fig. 3 is an enlarged horizontal section through the fastener.

40 Fig. 4 is a transverse vertical section thereof, and,

Fig. 5 is a perspective view on an enlarged scale of the fastener with the parts shown in juxtaposition ready for assembling.

45 In the embodiment illustrated a casement 1 is shown hinged in the usual manner to the frame 2 and is provided with an arm 5 pivoted at 4 to a bracket 3 carried by the lower rail of the casement.

50 The arm 5 is preferably constructed of angleiron U-shaped in cross section and substantially elbow shaped. One of the flanges of this arm is provided with a plurality of longitudinally spaced recesses 6 which also 55 extend into the body portion of the arm as is shown clearly in Figs. 2 and 5 said re-

cesses being designed to engage a coöperating element carried by the window sill as will be presently more fully described.

The arm 5 which is pivoted to swing horizontally carries a finger grip 7 at its free end to facilitate its operation and which is here shown as an upstanding headed stud although obviously it may be of other configuration.

60 A member 10 adapted to coöperate with the arm 5 is mounted on the window sill 8 and is constructed in the form of two separable members 11 and 15. The member 11 is shown disk shaped with two diametrically 65 opposite radially projecting apertured ears 12 to form fastening means for securing the device to the window sill. Rising from this disk shaped plate 11 adjacent the peripheral edge thereof is an upstruck bead 13 designed 70 to receive the cap shaped member 15, the flange 18 of which fits over the bead 13 and is designed to rotate in a manner presently 75 to be described.

75 The plate 11 has a centrally disposed aperture 14 to receive one end of a standard 16 the body portion of which is enlarged. The reduced end, which is mounted in the aperture 14, being upset or otherwise secured to the plate 11. The other end of this standard 16 is also reduced as shown at 17 to 80 form a neck which passes through an aperture in the cap member 15 and is equipped with a head 17' arranged outside the body portion of the cap. This standard 16 forms 85 a pintle on which the cap 15 rotates.

The flange 18 has oppositely disposed cut-out portions 19 to provide for the passage through the cap of the arm 5 and for the lateral shifting of the arm in the cap for a 90 purpose presently to be described. The arm 5 is so mounted in the cap 15 that the recesses 6 thereof will be positioned to interlockingly engage the standard 16 to hold 95 said arm in adjusted position and thereby 100 retain the casement 1 with which it is connected at any desired position either opened or closed or partially opened or closed. A spring 20 is mounted in the cap 15 and is 105 here shown coiled around a stud 21 which depends from the cap. This spring has two diverging arms 22 and 23, one of which carries an anti-friction roller 22', which bears against the arm 5 and the other against the inner face of flange 18 so that the spring 110 exerts its tension normally to force the arm 5 into locking engagement with the standard

16 and yet permits said arm to be shifted laterally a distance sufficient to release the standard from the notch 6 in the arm 5 when it is desired to slide the arm 5 through 5 the cap 15 for adjusting the arm.

From the above description it will be obvious that the cap 15 is rotatable on the standard 16 to provide for the swinging movement of the casement 1, it being seen 10 that when the parts are in the position shown in Fig. 1 and it is desired to close the casement 1 the hand grip 7 is grasped and moved laterally against the tension of the spring 20 to disengage it from the standard 15 16 and when a pull is exerted the arm 5 will operate to rotate the cap 15 into the position shown in Fig. 2 permitting arm 5 to swing into a plane parallel with the sill 8 on which the member 10 is mounted. When it is de- 20 sired to open the casement 1 the operation is reversed.

The preferred embodiment of the invention is disclosed in the drawings and set forth in the specification, but it will be understood that any modifications within the scope of the claims may be made in the construction without departing from the principle of the invention or sacrificing any of its advantages.

30 What is claimed is:

1. The combination with a supporting

structure having a member mounted to swing thereon; of a fastener for said member comprising an arm pivoted at one end to said member and provided with a plurality of longitudinally spaced recesses in one edge thereof, a coöperating element adapted to be mounted on said structure and carrying an upstanding standard with which the recesses of said arm are designed to engage, 35 and a spring carried by said element for forcing said arm into yieldable engagement with said standard.

2. A fastener of the class described comprising a member having means for attachment to a fixed support, a cap shaped member mounted to rotate on said fixed member and provided with a centrally disposed standard depending from its inner face and with oppositely disposed cutaway portions 50 in its side walls, an arm adapted to be pivoted at one end to a movable structure with its other end extending through the cutaway portions of the cap member, said arm having notches for interlocking engagement 55 with said standard, and a spring mounted to hold said arm yieldably engaged with the standard.

In testimony whereof, we affix our signatures hereto.

RUFUS BENZIGER.
FRANK GASS.
